UNITED STATES PATENT OFFICE.

NATHAN H. SCHERMER AND CHARLES G. HEILMAN, OF HIGHLAND PARK, MICHIGAN.

METHOD OF TREATING METALLIC BODIES ON ONE SURFACE.

Application filed October 24, 1927. Serial No. 228,437.

The present invention pertains to a novel method of modifying one surface of a metallic body while retaining the other surface in approximately its original condition. Such a method is useful and desirable in cases where the modifying treatment, if applied throughout the metallic body, would render it unfit for certain of its intended functions or for certain operations subsequently to be performed thereon. A specific example of such an instance is the case of a brake drum which requires one high carbon surface, while if the drum is carburized throughout, it will become too brittle for operations which may later be performed thereon.

Considering this example further, the metallic bodies are carburized on one surface while still in the form of disks or sheets prior to the shaping operations. The disks are arranged face to face in pairs, and these pairs are packed with carburizing material in a container in such a manner that each pair is entirely surrounded by this substance, but the members thereof have only their non-contacting surfaces exposed to the hardening material. The container is placed in an oven according to the usual carburizing process and may be cooled in view of the desired resulting hardness or the nature of the metal under treatment. After the container has been removed from the oven and the metallic bodies are cooled, they are stamped or otherwise treated to take the shape of a brake drum. The carburized surface of the body constitutes the wearing surface of the drum while the uncarburized surface of the metal is disposed on the other surface of the drum where carburizing is not necessary.

The invention is fully disclosed by way of example in the following description and in the accompanying drawing, in which—

Figure 1 shows a plan view and an edge view of the disk to be treated;

Fig. 2 is a plan view of the container partly broken away;

Fig. 3 is a transverse section of the container showing the bodies embedded in the hardening material;

Fig. 4 is an edge view of one of the carburized disks, partly broken away to show the effect of the treatment;

Fig. 5 is a plan view of the drum formed from the treated disk, partly broken away to show the nature of the treatment; and

Fig. 6 is a transverse section of the drum.

Reference to these views will now be made

by use of like characters which are employed to designate corresponding parts throughout.

As an example of the applicability of this process, we have chosen a brake drum to be formed from a sheet or disk 1 of suitable metal. As already indicated, it is desired to carburize only one surface of the disk and to leave the other surface unmodified. With this object in view, the disks are arranged in pairs 2 wherein the members of each pair are placed face to face and in marginal coincidence as clearly shown in Figure 3. In this condition the pairs of disks are embedded in a suitable carburizing material 3 contained in a receptacle 4, but it is to be noted that the pairs themselves are spaced from one another with the result that only the non-contacting surfaces of the members of each pair are exposed to the carburizing medium. There may be some flow of gas to the contacting faces, particularly at the edges, but not sufficient to produce any appreciable carburizing.

The container is equipped with a cover 5 and placed in an oven where it is heated according to existing processes of carburizing metal. After the completion of this operation, each body is carburized only at the surface which has been exposed to the substance 3 as indicated by the numeral 6 in Figures 4, 5 and 6, and the concealed surface will retain substantially its original character.

The bodies 1 are now shaped, as by stamping for example, into brake drums 7, and this operation is performed in such a manner that the carburized surface 6 will constitute the wear surface of the drum. The retention of the remaining surface 8 in substantially its original condition is beneficial to the shaping operation, and if the body 1 were carburized throughout, it would be more difficult to shape.

After this operation the metal may be further hardened by heating and quenching, if desired, although carburizing alone considerably improves the wearing qualities and increases the hardness.

Although the invention has been illustrated and described in connection with a brake drum, this disclosure of the invention is only illustrative, and it will be understood that the invention is applicable generally to the treatment of one surface of a body to the exclusion of the other surface, by methods other than carburizing, and that departure from the present disclosure may be

made in accordance with the scope of the invention as indicated by the appended claims.

What we claim is:

- ,5 1. A method of hardening one surface of metal blanks suitable for bending, consisting in arranging such untreated blanks in spaced pairs, with the members of each pair in juxtaposition relative to each other and in direct contact with each other to conceal one surface of each, whereby when exposed to a hardening medium only one surface of each is hardened.
- 10 2. A method of hardening one surface of metal blanks preparatory to bending, consisting in arranging such untreated blanks in spaced pairs, with the members of each pair in superposed contacting relation with each other to conceal one surface of each whereby
- 15 20 when exposed to a hardening medium only one surface of each is hardened.

3. A method of carburizing one surface of metal blanks suitable for bending, consisting in arranging such untreated blanks in spaced pairs, with the members of each pair in juxtaposition relative to each other and in direct contact with each other to conceal one surface of each whereby when exposed to a carburizing medium only one surface of each blank is carburized.

4. A method of hardening one surface of metal blanks suitable for bending, consisting in arranging such untreated blanks in spaced pairs and in embedding such pairs in a hardening medium with the members of each pair in superposed contacting relation with each other to conceal one surface of each whereby only one surface of each is hardened.

In testimony whereof we affix our signatures.
